(57) **CLAIM**

We claim the ornamental design for a MRI, as shown and described.

DESCRIPTION

FIG. 1 is a front perspective view of a MRI showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the dot dash enclosed portion in FIG. 2.

The broken lines in the figures show portions of the MRI which form no part of the claimed design.

The dot dash lines enclosing portions of the claimed design which are illustrated in enlargements form no part of the claimed design.
